UNITED STATES PATENT OFFICE

PHILIPP LAMPRECHT, OF CHICAGO, ILLINOIS

SWIMMING DEVICE

Application filed October 24, 1929, Serial No. 402,212. Renewed March 21, 1931.

This invention relates to new and useful improvements in swimming devices and more particularly to a device of this character which is adapted to be applied to the foot of the user.

One of the objects of my invention is the provision of a swimming device which can be quickly applied to the foot of the user and is provided with wings or blades movable in one direction for assisting in moving the user forwardly as he propels his feet through the water.

Another object of the invention is the provision of a swimming device which is extremely simple in construction and includes a central stationary part having blade or wing members hinged to the central part for swinging movement in one direction whereby they may be utilized for propelling a person through the water as they will offer very little resistance while being drawn through the water in one direction, but will offer resistance to the water when propelled in an opposite direction.

A further object of the invention is the provision of a swimming device having flexible attaching members secured to the stationary central part whereby the device can be quickly and easily attached to the foot of a user or removed therefrom.

With the above and other objects in view the invention consists in the novel features of construction, the combination and arrangement of parts hereinafter more fully set forth, pointed out in the claim and shown in the accompanying drawings, in which

Figure 1 is a top plan view of a swimming device constructed in accordance with my invention.

Figure 2 is a bottom plan view.

Figure 3 is a sectional view on the line 3—3 of Figure 2.

Figure 4 is a sectional view on the line 4—4 of Figure 2, and

Figure 5 is a side elevation showing the application of the device.

In carrying out my invention I provide a central body 1 which is shaped to conform somewhat to the shape of a foot with a heel portion 2, an instep portion 3 and a toe portion

4. At the extremity of the heel portion 2 I provide an upstanding arcuate heel guard 5 within which the rear portion of the heel is adapted to fit.

This heel guard 5 is made of any suitable type of metal and is secured at its lower end to the outer contour of the heel portion 2 of the body. Suitable strap members 6 are secured to opposite sides of the body 1 with the straps on one side of the body having buckles 7 attached to the outer ends thereof while the straps on the other side of the body are formed with openings to be engaged by the buckles whereby the straps may be extended across the instep and across the toe portion of a foot to hold the body 1 in position on the bottom of the foot.

Arranged upon opposite sides of the body 1 are the movable blades 8 and 9, each blade having its inner edge shaped to conform to the contour of the opposite side edges of the body 1 while the entire outer edges of both blades are so shaped that when they are in horizontal alignment with the body they form a rectangular shape as shown in Figures 1 and 2.

The blades 8 and 9 as will be noted are made comparatively thin with regard to the thickness of the body 1, but of light and durable material so that they will readily move through the water. The bottom of the body 1 is formed with apposed U-shaped channels or grooves 10 arranged in apposed relation as shown in Figure 2 with their ends opening at opposite sides of the body 1, with one end on each side opening at the toe portion and the other end opening out at the heel portion.

Movably mounted in the grooves 10 are the U-shaped rods 11 the longitudinal portions of which are rotatably mounted in suitable bearing blocks 12 adjacent each end of the intermediate portion of each rod. These bearing blocks are bolted to the underside of the body 1 and arranged transversely thereof so as to span both longitudinal portions of the grooves and form bearings for the longitudinal portions of each of the rods.

The ends of the rods are substantially flattened and project onto the lower faces of the blades 8 and 9 so that the extremities of the

rods are extended to the outermost edge of the blades and these ends are secured to the blades in any suitable manner.

It will be apparent that in using this device it is first strapped onto the feet of the user as shown in Figure 5 and as the feet are pulled through the water in swimming the blades 8 and 9 will move rearwardly behind the body to the dotted line position as shown 10 in Figure 3. However when the feet are pushed away from the body the blades will immediately move to a horizontal position with respect to the body 1 and offer considerable resistance to the water which will have 15 a tendency to move the body of the user forwardly.

It will be apparent from the foregoing that I have provided a simple and inexpensive swimming device which can be quickly and 20 easily applied to the foot of the user and as the user propels his feet forward and backward the blades 8 and 9 will move relative the body 1 to assist the user in propelling his body forwardly through the water as they 25 will offer very little resistance when being pulled forwardly through the water but will offer considerable resistance when the body is pushed back by the user.

While I have shown and described the preferred embodiment of my invention it will be apparent that various changes and alterations may be carried out without departing from the spirit of the invention or the scope of the appended claim.

35 I claim:

A device of the class described including a body portion of a shape to conform to the shape of a person's foot, means for securing the body to the foot of a person, blade members at opposite sides of the body, said body having U-shaped grooves arranged in opposed relation with their ends opening at opposite sides of the body with one end on each side opening at the toe portion and the other 40 end opening out at the heel portion, bearing blocks spanning the intermediate portion of the grooves at the ends thereof, U-shaped hinge members arranged in said grooves and rotatably mounted in said blocks, and the 45 extremities of said hinge members projecting beyond the edges of the body and secured to the blade members whereby the blade members are mounted for movement laterally in one direction with respect to the body.

50 In witness whereof I have hereunto set my hand this 10th day of September, A. D. 1929.

PHILIPP LAMPRECHT.
